UNITED STATES PATENT OFFICE.

JOHN D. A. JOHNSON, OF OMAHA, NEBRASKA.

GEARING.

1,078,146.

Specification of Letters Patent.

Patented Nov. 11, 1913.

Application filed August 28, 1911. Serial No. 646,404.

To all whom it may concern:

Be it known that I, JOHN D. A. JOHNSON, a citizen of the United States, residing at Omaha, in the county of Douglas and State 5 of Nebraska, have invented certain new and useful Improvements in Gearing, of which the following is a specification.

My invention relates to washing machines and the object thereof is primarily to provide a simple and efficient construction and arrangement of driving and reversing mechanism for the wringer, which mechanism is adapted to be driven by the driving connections for the agitator of the washing 15 machine.

Various features of advantage and utility in my construction will be apparent from the description hereinafter given.

In the drawings, Figure 1 is a side elevation of my complete washing machine; Fig. 2 a sectional elevation on the line 2—2 of Fig. 3; Fig. 3 a plan view of the machine; Fig. 4 a cross section on the line 4—4 of Fig. 3 and Fig. 5 a section on the line 5—5 of 25 Fig. 3.

For the purpose of a clear and definite disclosure of my invention I have herein shown and will hereinafter describe a machine representing one embodiment of my 30 invention although it will be understood that changes may be made, particularly as to details, without departing from the spirit and scope of my invention and claims.

Referring to the machine herein shown 35 the washing machine comprises a washing receptacle 1 supported on legs 1^a and containing any usual form of agitator (not shown) such as for instance that illustrated in Howe Patent No. 711,317 dated October 14, 1902, which also illustrates the same general character of driving connections for the agitator and as to which I make no claim herein. These driving connections consist of a reciprocating rack bar 2 adapted 40 to mesh with the pinion 3 which is secured to the vertical shaft 4 of the agitator. This rack is pivotally connected at the point 2^a with a crank arm or pitman 5 which is pivoted at its outer end to a bevel gear 6, which 45 has two sets of gear teeth one set 6^a and another set 6^b, the former of which meshes with a pinion 7 formed in the present instance as an integral part of a wheel or pulley 8. This pulley is secured to a horizontal 50 shaft 9 which is journaled in a bracket 10

mounted on the top of the washing receptacle. This pulley is operated by a suitable prime mover which in the present instance is an electric motor 11 whose armature shaft has a small pulley 12 operatively connected 60 with the pulley 8 by means of the belt 13. The gear wheel 6 is secured to a vertical shaft 14 which is journaled in the bracket 10 and which by preference and as shown is extended downwardly a comparatively 65 considerable distance for a purpose herein-after explained, the lower end being held in place by a bearing 15.

Upon the top surface of the washing receptacle I provide a support or platform 16 which is adapted to support any suitable wringer such as that illustrated at 17 and the reversible driving connection or clutch mechanism therefor and also the electric motor hereinbefore referred to. As shown 70 this support overhangs or projects beyond the sides of the receptacle thereby providing a place of attachment for the electric motor which depends therefrom as clearly shown in Fig. 1, the motor and the reversible clutch being in the same vertical plane, 75 one above the support and the other below.

The clutch consists of two bevel gears 18 and 19 connected together by a central portion 20 which in the present instance is integral therewith. The hub portion of the gear 19 has an angular socket 19^a adapted to receive the angular head 21^a of a shaft 21 for driving the wringer. These bevel gears are journaled within a housing which 80 is divided centrally into two parts 22 and 23, the former of which is mounted upon and secured by means of its foot pieces or bracket 22^a to an extension 10^a of the bracket 10 which is itself secured to the support 16, 85 the two sections or halves of the housing being clamped together by means of the screw bolts 24. By preference the foot pieces are adjustably secured to said bracket 90 extension by the usual bolt and slot connection indicated at 22^b. Within the housing and between the two bevel gears is arranged a clutch connector which is in the form of a bevel pinion 25 secured to the inclined shaft 26 which is adapted to be shifted or oscillated in order that the bevel pinion may 95 mesh with the one or the other of the two gears 18 and 19 or may be left in intermediate or neutral position out of engagement with either of these gears. This shaft 100

110

26 has, in the present instance, a bearing bracket 27 which is pivoted upon the depending shaft 14 of the gear wheel 6, with the result that said shaft is pivoted in the line of the axis of rotation of the wheel 6. Intermediate its length this shaft 26 is provided with a pinion 28 which meshes with the bevel teeth 6^a on the gear wheel 6, whereby the motion of the latter wheel is communicated to the shaft 26 and consequently to its pinion 25.

15 A hand-operated clutch shifter is provided for the shaft 26, the same consisting of a rod 29 extending into the housing through a horizontal slot 30, Fig. 4, and curved near its middle, to accommodate the central portion 20 of the clutch device. The lower or inner end of this shifter is formed as a socket 29^a to fit upon the outer end of the shaft 26 above its pinion 25. In order to hold this shifter in proper operative position and to prevent its being removed from its engagement from the shaft 26, I provide the upper surface thereof, intermediate its 25 length, with a lug 29^b which is adapted to coöperate with the upper inner edge of the slot 30 in the housing, Fig. 2. For the purpose of holding the shifter in either one of its three positions I provide the same with a 30 spring-operated latch 31 pivoted thereto and having a forwardly projecting finger 31^a adapted to enter any one of the holes 32 in the housing according to the particular adjustment of shifter. It will be understood that it is not essential that the shaft 14 be extended downwardly to form a pivot for the inner end of the shaft 26 or that such shaft be pivoted below the gear wheel 6, the only essential feature in this regard being that the shaft be pivoted in the line of the axis of rotation of the wheel 6 so that in the different shifted positions of the shaft 26 there shall be no clamping or binding between the gear wheel 6 and the pinion 28.

45 When the parts are in the relative position shown in Fig. 3 which is a neutral position of the shifter and pinion 25 the washing machine proper only will be operated and the wringer will not be operated. However 50 when the shifter is moved to one of the lateral holes 32 so as to bring the pinion 25 into mesh with one of the gears 18 and 19, the wringer will be operated in one direction and if the shifter is moved to the other 55 extreme position the pinion 25 will be brought into mesh with the other bevel gear so as to rotate the wringer in the opposite direction, it being understood that the pinion 28 is always in mesh with the gear wheel 6 and is always rotated in the same direction. The construction and arrangement of parts above described constitutes a very simple but effective mechanism for the objects 60 in view and a mechanism which is moreover 65 comparatively inexpensive and economical

of manufacture which are important considerations in machines of this character.

I claim:

1. The combination of a driving wheel rotatable in a fixed plane and reversing driving connections comprising two rotatable members having the same axis of rotation, and a shiftable device always in operative engagement with said driving wheel and adapted to be placed in engagement with 70 one or the other of said members to connect the wheel with one or the other thereof, said device being pivoted at one end in the axis of rotation of the wheel.

15 2. The combination of a driving wheel rotatable in a fixed plane and reversing driving connections comprising two rotatable members having the same axis of rotation, and a shiftable device always in operative engagement with said driving wheel and adapted to be placed in engagement with 75 one or the other of said members to connect the wheel with one or the other thereof, said device being pivoted at one end in the axis of rotation of the wheel.

20 3. The combination of a driving member rotatable in a fixed plane and having a bearing shaft, reversing driving connections comprising two driven members arranged 80 to rotate on the same axis, a bearing bracket pivoted on said shaft, and a shiftable device supported by said bracket and adapted to swing at its outer end in substantially the line of said axis of rotation, said device being in constant engagement with 85 said driving member and adapted to be placed into engagement with one or the other of such members.

25 4. In a washing machine, the combination of a driving gear rotatable in a fixed plane, and reversing driving connections comprising two members and a shiftable device including a rotatable member adapted 90 to coöperate with one or the other of said members, a shaft on which said member is mounted and which is pivoted in the line of the axis of rotation of said gear, and a pinion secured to said shaft and in mesh with 95 the gear at all times.

30 5. The combination of a driving member in the form of a bevel gear, a driving shaft, therefor, reversing driving connections comprising two opposed gears mounted to rotate on a common axis, and a shiftable device adapted to operate between the bevel gear and one or the other of the two opposed gears and comprising a driven shaft inclined 100 to the driving shaft and pivoted thereto at its inner end, a bevel pinion mounted on the 105

110 shaft and in mesh with the bevel gear.

driven shaft toward its inner end and adapted to mesh with the bevel gear, and a gear mounted on the driven shaft toward its outer end and adapted to mesh with one or 5 the other of the two opposed gears.

6. In a washing machine, the combination of a rotatable driving member and reversing driving connections comprising two gears having opposed teeth and mounted to 10 rotate on a common axis, a shaft pivoted at one end, two pinions mounted thereon, one in constant engagement with said driving member and the other adapted to be placed in engagement with one or the other of said 15 two gears, and means for shifting said shaft.

7. In a washing machine, the combination of a rotatable driving member and reversing driving connections comprising two gears having opposed teeth, a shaft pivoted 20 at its inner end in the line of the axis of rotation of said driving member, a pinion at the outer end of such shaft adapted to be placed in engagement with one or the other of said 25 two gears, and a second pinion on the shaft which is in engagement with said driving member.

8. In a washing machine, the combination of a rotatable driving member and reversing driving connections comprising two gears 30 having opposed teeth and mounted to rotate on a common axis, a shaft, a bearing bracket therefor located at its inner end and pivoted in the line of the axis of rotation of said driving member and arranged to swing 35 bodily on such axis, a pinion at the outer end of such shaft adapted to be placed in engagement with one or the other of said two gears, and a second pinion in the shaft which pinion is in engagement with said driving 40 member.

9. In a washing machine, the combination of a rotatable driving member and reversing driving connections comprising two gears having opposed teeth and mounted to 45 rotate on a common axis, a shaft, a bearing bracket therefor located at its inner end and pivoted in the line of the axis of rotation of said driving member and arranged to swing bodily on such axis, a pinion at the 50 outer end of such shaft adapted to be placed in engagement with one or the other of said two gears, a second pinion on the shaft which pinion is in engagement with said driving member, and a shifter engaging the 55 outer end of said shaft.

10. In a washing machine, the combination of a rotatable driving member and reversing driving connections comprising two gears having opposed teeth, a shaft, a bearing 60 bracket therefor located at its inner end and pivoted in the line of the axis of rotation of said driving member, a pinion at the outer end of such shaft adapted to be placed in engagement with one or the other of said 65 two gears, a second pinion on the shaft

which pinion is in engagement with said driving member, and a shifter engaging the outer end of said shaft, said two gears being connected by a central cross shaft portion and said shifter being curved intermediate its length to accommodate said shaft portion. 70

11. In a washing machine, the combination of a rotatable driving member and reversing driving connections comprising two gears having opposed teeth and mounted to rotate on a common axis, a shaft, a bearing bracket therefor located at its inner end and pivoted in the line of the axis of rotation of said driving member and arranged to swing bodily on such axis, a pinion at the outer end of such shaft adapted to be placed in engagement with one or the other of said two gears, a second pinion on the shaft which pinion is in engagement with said driving member, a shifter engaging the outer end of said shaft, and means for normally holding the shifter in its operative relationship. 75 80 85

12. In a washing machine, the combination of a rotatable driving member and reversing driving connections comprising two gears having opposed teeth, a shaft, a bearing bracket therefor located at its inner end and pivoted in the line of the axis of rotation of said driving member, a pinion at the outer end of such shaft adapted to be placed in engagement with one or the other of said two gears, a second pinion on the shaft which pinion is in engagement with said driving member, a housing for said gears, and a shifter extending through said housing and operatively connected with the outer end of said shaft. 90 95 100

13. In a washing machine, the combination of a rotatable driving member and reversing driving connections comprising two gears having opposed teeth, a shaft, a bearing bracket therefor located at its inner end and pivoted in the line of the axis of rotation of said driving member, a pinion at the outer end of such shaft adapted to be placed in engagement with one or the other of said two gears, a second pinion on the shaft which pinion is in engagement with said driving member, a housing for said gears, and a shifter extending through said housing and operatively connected with the outer end of said shaft, said shifter having means co-operating with the housing to prevent withdrawal of the shifter when the housing is in place. 105 110 115 120

14. In a washing machine, the combination of a rotatable driving member and reversing driving connections comprising two gears having opposed teeth, a shaft, a bearing bracket therefor located at its inner end and pivoted in the line of the axis of rotation of said driving member, a pinion at the outer end of such shaft adapted to be 125 130

placed in engagement with one or the other of said two gears, a second pinion on the shaft which pinion is in engagement with said driving member, a housing for said gears, and a shifter extending through said housing and operatively connected with the outer end of said shaft, said shifter having

a hand latch cooperating with the housing for holding the shifter in its different positions.

JOHN D. A. JOHNSON.
